UNITED STATES PATENT OFFICE.

EDWARD H. WARREN, OF RENTIESVILLE, OKLAHOMA, ASSIGNOR OF ONE-HALF TO
ANDREW J. CARLOW AND J. HOWARD CARLOW, BOTH OF CHECOTAH, OKLAHOMA.

TRAIN-PIPE COUPLING.

1,162,117.

Specification of Letters Patent. Patented Nov. 30, 1915.

Application filed January 21, 1915. Serial No. 3,614.

To all whom it may concern:

Be it known that I, EDWARD H. WARREN, a citizen of the United States, residing at Rentiesville, in the county of McIntosh and 5 State of Oklahoma, have invented certain new and useful Improvements in Train-Pipe Couplings; and I do declare the following to be a full, clear, and exact description of the invention, such as will enable others 10 skilled in the art to which it appertains to make and use the same.

My invention relates to improvements in train pipe couplers and has for its object to improve upon the general construction of 15 devices of this character to such an extent, as to provide a very simple and efficient device which may well be carried directly by the ordinary car coupler.

A further object is to equip the couplers 20 with novel means for opening valves used therein, which valves control the passage of steam, or compressed air from one coach to another.

Yet another object is to provide a novel 25 form of frame for supporting the pipe coupler beneath the car coupler, and to so construct the mounting of this frame as to allow the latter to be adjusted longitudinally irrespectively of the coupler, and to move 30 inwardly and outwardly as said coupler yields against its spring.

In addition to the above objects, the invention further aims to equip the frame above described with means whereby the attachment 35 of a second and similar frame, to support a supplemental coupler, is made possible.

With the above objects in view, the invention resides in certain novel features of construction and combination hereinafter described and claimed and shown in the drawings wherein:—

Figure 1 is a side elevation partly in section, showing the application of a pair of 45 couplers to a pair of cars, the couplers being shown in juxtaposition; Fig. 2 is a horizontal section as seen along the plane of the line 2—2 of Fig. 1 and showing plan views of the two couplers; Fig. 3 is a view similar to Fig. 1 but showing the couplers interengaged; Fig. 4 is a horizontal section taken along the plane of the line 4—4 of Fig. 3; Fig. 5 is a vertical transverse section taken along the plane of the line 5—5 of Fig. 4, 55 and showing more particularly the construc-

tion of the valves employed; Fig. 6 is an additional detail transverse section as seen on the line 6—6 of Fig. 1; Fig. 7 is a perspective view showing the two couplers in juxtaposition; Fig. 8 is a perspective view of one 60 of the supporting frames; and Fig. 9 is a similar view of the supplemental supporting frame above mentioned.

In these drawings, constituting a part of this application, portions of a pair of cars C 65 are shown, these cars being provided with any appropriate type of coupler heads H which are provided with the usual shanks S sliding through bearings B and which are equipped with the usual springs s for allowing them to move inwardly and outwardly 70 to the necessary extent.

In the present embodiment, the bearings B are shown as secured directly to the bottom of the car C and as having laterally projecting ears 1 on their lower sides, (see more particularly Fig. 6). To the ears 1 of each car, a pair of angle iron tracks 2 is secured, these tracks lying parallel to each other, extending longitudinally beneath the shank S, 80 and slidably supporting a T-head 3 which rises from the inner end of a longitudinally extending supporting yoke 4, the outer end of this yoke being secured by a clamp 4' to the shank S adjacent its head H. 85

By reference to the drawings, it will be seen that the structure just described is duplicated on each car C, it being thought sufficient however, to describe that upon one car only. Furthermore, the yokes 4 support a pair of frames 5 in which the train pipe couplers 6 are mounted, but since the construction of these frames and couplers is identical, it is thought that a description of one will suffice. 90

Each frame 5 comprises a top plate 7 which is adjustably secured by a pair of clips 8 to the yoke bar 4, an inner end plate 9 which depends from the inner end of the top plate 7, a pair of bars 10 which depend from the outer corners of said top plate, and a bottom plate 11 which is secured in any appropriate manner to the lower ends of the bars 10 and plate 9, these bars and plate being here shown as extending below 100 said bottom plate and as having openings in their lower ends, which openings are adapted for a purpose to be described. Furthermore, the plate 11 is shown as extending 105 outwardly from the bars 10 as seen at 12 and 110

as having a pair of upstanding ears 13 on its outer corners.

Slidably mounted between the bars 10 and ears 13 and normally resting upon the plate 11, is the rectangular neck 14 of the coupler 6, the inner end of this coupler having a T-head 15 which is positioned inwardly from the inner edges of the bars 10 and which is adapted to strike these bars when moved outwardly beyond a predetermined extent, thus preventing the entire removal of the coupler. The inner end of the T-head 15 rests against an upright plate 16 whose upper and lower ends abut the top and bottom plates 7 and 11. This plate 16 is spaced outwardly from the rear end plate 7 as clearly seen in Figs. 1 and 3 and a cushioning device is interposed between said plates 9 and 16. This cushioning device is shown in the present application as comprising a U-shaped leaf spring 17 secured to the plate 9 and having its ends extended laterally and contacting with the plate 16, said cushioning device also including a pair of coil springs 18 whose inner ends fit within appropriate sockets in the end plate 9 while their outer ends bear against the outer ends of the spring 17 as shown. By this construction, the coupler 6 is normally forced outwardly to the necessary extent.

The outer end of the coupler 6 is provided with a pointed nose 20, one of whose upright sides is flattened as seen at 21, while its opposite side may be shaped in any appropriate manner. Spaced inwardly from the point of the nose 20 and opening toward the same, is a semi-cone shaped socket 22, this socket being adapted to receive the nose 20 of the other coupler when the two members are brought together as seen in Fig. 3.

Rising from the socket 22 or from another appropriate part of the coupler 6, is an upright flange or its equivalent 23, to which a horizontal rack bar 24 is secured by bolts or other appropriate means, the teeth of this bar preferably lying parallel with the flat face 21 as shown, while spaced laterally from the smooth side of the rack bar 24 is a pinion 25 which is formed integrally with or secured in any appropriate manner to the upper end of an upright cylindrical valve stem 26, this stem having two or more ports 27 which, when the valve stands in the position seen in Fig. 5, are adapted to register with ports 28 which are formed transversely through the outer end of the neck 14 and provided at their outer ends with gaskets 21' lying flush with the flat faces 21. The train pipes 29 are connected by nipples or other appropriate devices to one end of the ports, while the other ends thereof discharge through the flat upright faces 21 as clearly shown in the various figures of the drawings.

65 Under normal conditions, when the cars

are uncoupled, the valve 26 closes the ports 28, but when the cars are coupled and the two couplers 6 are brought together, the noses 20 of these couplers engage the sockets 22 and the racks 24 of the two couplers engage the pinions 25 thereof, thus rotating said pinions and the valves to open the latter, or in other words, to cause their ports 27 to register with the ports 28. At the same time, the various ports 28 in the two couplers 6 align, thereby establishing communication between the train pipes of the two cars. When the parts stand in active position, the cushioning devices before described are compressed, these devices now acting to effectively retain the pipe couplers in such position. Furthermore, as the two car couplers move inwardly and outwardly as the cars are being drawn over the road, the hose couplers 6 will move inwardly and outwardly therewith, it being therefore evident that there is no tendency on the part of these last named couplers to separate.

It is a well known fact that the various cars of some railway companies are spaced greater distances from the track than those of other companies, it being therefore expedient to provide means whereby the lowermost of the couplers 6 may be raised to the necessary extent. For this purpose, filling blocks or bars 40 are employed, these bars being normally suspended from the cars as seen in Figs. 1 and 3, but being capable of insertion beneath the couplers 6, when the latter are raised within their supporting frames, said bars being then secured in place by set screws 41 as shown more particularly in Fig. 8. By this means, the couplers 6 may be raised to the necessary extent for aligning them properly.

Hereinbefore, I have described the fact that the lower ends of the plate 9 and the bars 10 depend below the bottom plate 11, this provision being made in order that a supplemental frame 5' may be suspended beneath the frame 5, this frame being constructed in identically the same manner as said frame 5, with the exception that it is provided with no top plate. Furthermore, the upper ends of the bars 10' and the end plate 9' are preferably offset to contact with the outer sides of the bars 10 and plate 9, it being then only necessary to insert a plurality of bolts through the overlapping portions of these members to secure the supplemental frame in position.

I have described the fact that the clips 8 are adjustable longitudinally on the yoke 4, this being done in order that the frames 5 may be adjusted outwardly or inwardly to the necessary extent to allow the two couplers 6 to properly inter-engage. These frames may then be held in their adjusted position not only by tightening the bolts by which the clips 8 are secured to the plate 7, 130

but by tightening turn buckles 50 with which brace rods 51 are provided, the lower ends of these rods being attached in any appropriate manner to the frames 5 while there upper ends are secured to the clamps 4'.

From the foregoing description, taken in connection with the accompanying drawings, it will be seen that a comparatively simple structure has been provided for carrying out the objects of the invention, yet that such structure will be highly efficient in operation.

In the drawings, certain specific details of construction have been shown for accomplishing probably the best results, and in the preceding such details have been described, but it will be evident that I need not be limited thereto otherwise than to the extent to which the appended claims re-

strict me.

I claim:

1. A coupler head of the class described having a port, a rotary tapering valve for closing and opening said port, a gear se-

cured to one end of said valve, and a longitudinally extending rack bar carried by the coupler head and spaced from the gear, combined with an additional and similarly constructed head, the rack bar of one head being adapted to engage and rotate the gear of the other head when the two couplers are brought together.

2. A coupler head of the class described having a port, a valve for closing and opening said port, a gear for operating said valve, and a longitudinally extending rack bar carried by the coupler head and out of mesh with the gear, the gear and rack being designed for coaction with an additional gear and rack on a second coupler head.

In testimony whereof I have hereunto set my hand in presence of two subscribing witnesses.

EDWARD H. WARREN.
